PROCESS OF ERECTING ROOFS FOR BUILDINGS AND THE LIKE

Henry G. Onstad, Chicago, Ill., assignor to James Stewart Corporation, Chicago, Ill., a corporation of Illinois

Application December 10, 1932, Serial No. 646,577

13 Claims. (Cl. 108—1)

My invention relates to improvements in processes of erecting roofs for buildings and the like and has for one object to provide a new and improved process of erecting whereby roofs, floors 5 and building walls may be erected and installed more rapidly, easily and cheaply than has heretofore been the case. Another object of my invention is to provide a process of erecting a roof structure wherein a plurality of long continuous 10 roof sheets are drawn into place anchored and the roof is assembled from them without the use of scaffolding or supporting structures. Other objects will appear from time to time throughout the specification and claims.

15 In general, I propose to provide a roof or similar structure wherein there will be two anchorage abutments, one of them serving as the ridge pole, the other as the eave pole. These abutments when I am dealing with the roof will be 20 one above the other and spaced apart, perhaps in some instances many hundreds of feet. I propose to form a roof section which will consist in a thin steel plate, perhaps six feet or more in width and in length somewhat more than the 25 linear distance between the ridge pole and the eave pole. This sheet may be performed at the mill and shipped as a unit or may be built up by assembling or riveting or bolting a plurality of short sheets to give a sheet whose length is 30 somewhat greater than the distance between the ridge pole and the eave pole. If this strip is assembled in the field, it will be assembled on a templet, preferable adjacent sheets will be butt-welded together except for the joint between two 35 adjacent sheets which will be lap-welded so as to avoid the necessity of accurately cutting the sheets to length. A plurality of these strips will be prepared and will be laid out on the ground at one side of the eave pole in general alignment 40 with the position they are to assume with the roof. The upper and lower edges of these strips will preferably be reinforced by a cross reinforcing strip welded or perhaps riveted in place and bolt or rivet holes will be driven through the 45 strip and the reinforcement. One or more pulleys will be erected adjacent the ridge pole and cables will be passed down over these pulleys to a bridle attached to the upper end of the strip. An anchorage cable will be attached to the lower 50 end of the strip and these cables will be associated with hoisting engines so that the upper end of the strip may be drawn up over the eave pole and up to the ridge pole, the brake at the rear end of the strip maintaining a tension on 55 the spring so that it will not sag down too far.

This manipulation will continue until the upper edge of the strip has been brought into engagement with the ridge pole and the lower edge into engagement with the eave pole when by bolting, riveting or welding the strip will be fastened at its upper and its lower end to the ridge and eave pole, after which the strip hangs freely under the influence of gravity in a flat curve between the two poles. The process will be continued with the next and succeeding strips until all the 10 strips have been arranged side by side to form the roof. Then an operator using the strips as his scaffolding will weld adjacent strips together, thus making a weathertight roof capable of supporting its own weight and requiring no scaffolding for its erection and requiring no intermediate supports between the upper and lower edges of the roof.

15 As the welding is being done, some of the adjacent strips will not be welded but will be cut away if they have not previously been preformed so as to provide expansion joints or clearance between some of the adjacent strips. The weathertight closure comprising a relatively thin flexible metallic sheet will be welded to the opposed edges 20 of such strips in connection with the welding operation. This is obviously necessary to permit expansion and contraction of the roof sheet in a direction perpendicular to the axis of the individual strips, expansion and contraction parallel with the axis being of course taken care of by change in the length of the arc.

25 If desired the brake and hold back at the rear end of the strip may be dispensed with. In that case two or more cables will be strung from the ridge pole to the eave pole and the strip will be hauled up along the cables as along a track. Under these circumstances some kind of guide means would of course be required to keep the 30 strip from sliding off the cable.

35 Preferably it is a welded arrangement but of course the strips might be allowed to overlap and be riveted together but such a structure would not be nearly as cheap, convenient or satisfactory.

40 This same system might be applied to the erection of side panels for a building or to the erection of floor panels but in any event it consists in preforming on the ground the long panel or sheet of metal of the proper length and then taking hold of one end of it and hauling it into position and holding it there until it is fastened in 45 position without the use of any special scaffolding while using the metal itself as its own tension supporting element. It will be noted that the 50 55

structure erected according to my process is disclosed and claimed in my copending application Ser. No. 646,578, filed December 10, 1932.

My invention is illustrated more or less grammatically in the accompanying drawings, wherein—

Figure 1 is a plan view of the structure partially completed showing the method in which assembly takes place;

10 Figure 2 is a section along the line 2—2 of Figure 1;

Figure 3 is a modified view similar to Figure 1; Figure 4 is a modified view similar to Figure 2;

15 Figure 5 is a section along the line 5—5 of Figure 1;

Figure 6 is a section along the line 6—6 of Figure 1;

Figure 7 is a section along the line 7—7 of Figure 4;

20 Figure 8 is a section through a modified form of construction;

Figure 9 is a section through a modified form of construction.

Like parts are indicated by like characters throughout the specification and drawings.

My invention for the purpose of convenience is illustrated as applied to a grain elevator, that being a type of structure to which it is especially well adapted but it will be understood, of course, 25 that the invention might be used in connection with many different types of structure. As applied to the grain elevator, we have a series of concrete bins or silos A A¹ A² tied together or built together in a unitary structure in any suitable manner. In this instance, the bins A A¹ form 30 the ends of the house, the bins A² form one side, thus bounding three sides of a relatively large rectangular area which may be used as a working space or a storage space in the interior of the 35 house. Along the open side is a relatively narrow structure A³ which may be used as a working space or for a conveyor or for any other suitable purpose. It comprises in general diagonal columns A⁴, outer wall columns A⁵, roof beams A⁶, 40 and diagonal tension taking studs A⁷ extending from the tops of the column A⁴ to an anchorage A⁸ which for the purpose of convenience is located beneath the lower ends of the column A⁵. This structure is 45 provided with the usual kind of roof A⁹ and side walls or sheathing A¹⁰.

This roof A⁹ along its upper inner edge, immediately adjacent the junction points of the columns A⁴ and tension members A⁷ is provided with 50 a concrete or other suitable reinforcing anchorage ledge B having reinforcing bars B¹ associated with an angle iron B² on the rear side of the anchorage ledge and extending throughout the whole length of the structure. The upper face 55 of the member B is flat and upwardly and inwardly inclined as at B³. The upper flange of the angle B² is apertured along its entire length as at B⁴.

Referring now to the upper end of the structure, the silos or bins carry at their top a horizontal concrete roof slab C which projects out between adjacent bins to be substantially tangent to the outer extremity of each bin. This roof is thickened as at C¹, the thickened portion tying 60 in to the circular walls of the bin. Bars C² are embedded in the roof and extend out to the angle plate C³, the lower flange of the angle plate being downwardly inclined to the lower structure A³ above referred to. The part of the roof slab immediately above this angle plate is filled with 65

any suitable packing or insulating material as at C⁴. The flange C⁵ of the angle plate is perforated along its entire length.

The roof proper is formed of a series of steel strips D. These separate steel strips are preferably preformed in any suitable templet by welding or riveting from separate short strips as at D¹ although of course, under some circumstances the whole strip might be shaped from the material cut to proper length.

In my preferred exemplification, however, the separate strip elements are butt welded as at D¹, one strip being lap welded as at D² for the purpose of convenience so as to make it unnecessary to cut the strips accurately in the field to fit the templet L. The 10

assembled strip is provided at each end with a 15 welded reinforcing plate D³ D⁴, which plate is spaced slightly inwardly from the end of the strip. Holes D⁵ are punched or drilled through

the strip and through the plate and holes D⁶ are 20 punched or drilled at the end beyond the reinforcing strip. The structure is erected by preparing or placing the prepared roof strip in position

on the ground in line with the position it is 25 to occupy on the roof. It is then moved into position on the roof with the holes D⁵ in the reinforcing plate D⁴ in line with the holes in the flange C⁵ and with the holes D⁵ in the reinforcing plate D³ in line with the holes in the angle flange B².

The bolts D⁸ having previously been 30 placed in the flange C⁵ will be caused to pass through the holes in the plate D⁴ and the bolts D⁷ can also be placed through the holes D⁵ in the reinforcing plate D³ and also in the flange B².

When these bolts are tightened up they may be 35 welded or riveted, or bolts or rivets alone may be used to rigidly fasten the upper and lower end of each strip to its anchorage at top and bottom of the structure. The structure is completed by placing strip after strip side by side until a 40

structure such as is found in Figure 1 has been made. The two ends of each strip being rigidly fastened to an anchorage, the strip will hang 45 freely in a catenary curve between its two anchorage points and as expansion and contraction takes place, the curve will change but the anchorage needs not to move and change in the curve will take care of change in the total length.

L¹ is a hoisting yoke adapted to be bolted to the leading edge of the plate. L² is a hold back 50 yoke adapted to be bolted to the rear end of the plate.

M is a sheave erected at the ridge pole of the structure. M¹ is a roller removably mounted at the eave pole of the structure. M² are cables passing

from the hoisting yoke over the roller over the sheave and then to the hoisting engine M³. M⁴ is a cable passing from a track drum associated with the hoisting engine M⁵ to the hold back

yoke so that the operator may by manipulating 60 the cables pull the leading end of the strip forward out of the templet L over the roll and up to the ridge pole, meanwhile holding back on the rear end of the strip to prevent too sharp a sag.

When the strip is positioned with its ends in juxtaposition with the upper and lower supports it may easily be bolted or riveted in place, whereupon the yokes may be removed and the process 65 continued indefinitely.

In the modified form shown, instead of using 70 the hold back anchorage, cables N N¹ are used hanging between the two abutment or supporting members. Shoes N² are bolted to the plate and

guide the plate along the cable. The single hoisting rope N³ passing from the yoke over the sheave 75

on the ridge pole down to the hoisting engine may be used to raise the metallic strip along the cables which act as tracks, in this case no hold back is needed.

5. In the modified form of structure shown in Figures 8 and 9, the operation so far as the manipulation of the sheet is concerned is exactly the same but the position of the sheet itself when the job is done is different in that the sheet may 10 serve as a floor support or as a wall or sheathing but the manipulation or control is the same in each case.

I claim:

1. The process of erecting a roof which consists 15 in erecting two spaced supporting members, preparing a relatively narrow elongated metallic strip in length somewhat greater than the distance between said supporting members, moving the strip bodily as a unit into position with each end in juxtaposition with one of said supporting members, fastening such ends to the adjacent supporting members, continuing the process with a second strip and then fastening the adjacent edges of the strips together.

25. 2. The process of erecting a roof which consists in erecting two spaced supporting members, attaching a plurality of metallic plates end to end to form a narrow elongated metallic strip in length somewhat greater than the distance between said supporting members, moving the strip bodily as a unit into position with each end in juxtaposition with one of said supporting members, fastening such ends to the adjacent supporting members, continuing the process with a second strip and then fastening the adjacent edges of the strips together.

30. 3. The process of erecting a roof which consists in erecting two spaced supporting members, preparing a relatively narrow elongated metallic strip in length somewhat greater than the distance between said supporting members, placing said strip on the ground in general alignment with the position it is ultimately to assume and moving the strip along as a unit into position with each end in juxtaposition with one of said supporting members, fastening such ends to the adjacent supporting members, continuing the process with a second strip and then fastening the adjacent edges of the strips together.

35. 4. The process of erecting a roof which consists in erecting two spaced supporting members, attaching a plurality of metallic strips end to end to form a narrow elongated metallic strip in length somewhat greater than the distance between said supporting members, placing said strip on the ground in general alignment with the position it is ultimately to assume, moving the strip longitudinally as a unit into position with each end in juxtaposition with one of said supporting members, fastening such ends to the adjacent supporting members, continuing the process with a second strip and then fastening the adjacent edges of the strips together.

40. 5. The process of erecting a roof which consists in erecting two spaced supporting members, preparing a relatively narrow elongated metallic strip in length somewhat greater than the distance between said supporting members, placing said strip on the ground in general alignment with the position it is ultimately to assume, attaching a tension member to the forward end of the strip and a hold back member to the rear end of the strip, pulling on the tension member to move the strip until its forward end is in immediate juxtaposition with one of the supporting members while holding back on the rear end of the strip until its rear end is in immediate juxtaposition with the other member, then fastening such ends to the adjacent supporting members and continuing the process with the second strip and then fastening the edges of the adjacent strips together.

45. 6. The process of erecting a roof which consists in erecting two spaced supporting members, attaching a plurality of metallic strips end to end to form a narrow elongated metallic strip in length somewhat greater than the distance between said supporting members, placing said strip on the ground in general alignment with the position it is ultimately to assume, attaching a tension member to the forward end of the strip and a hold back member to the rear end of the strip, pulling on the tension member to move the strip until its forward end is in immediate juxtaposition with one of the supporting members while holding back on the rear end of the strip until its rear end is in immediate juxtaposition with the other member, then fastening such ends to the adjacent supporting members and continuing the process with the second strip and then fastening the edges of the adjacent strips together.

50. 7. The process of erecting a permanent structure which consists in erecting a plurality of generally horizontal supporting members, preparing a relatively narrow elongated metallic strip whose length is somewhat greater than the total width of the structure, moving the strip bodily as a unit into position in the structure and permanently attaching the strip to said horizontal supporting members.

55. 8. The process of erecting a roof which consists in erecting two spaced supporting members, preparing a relatively narrow elongated metallic strip in length somewhat greater than the distance between said supporting members, placing said strip on the ground in general alignment with the position it is ultimately to assume, attaching a tension member to the forward end of the strip and a hold back member to the rear end of the strip, such tension and hold back members forming the sole tension support for the metallic strip as the latter is moved into position, pulling on the tension member to move the strip until its forward end is in immediate juxtaposition with one of the supporting members while holding back on the rear end of the strip until its rear end is in immediate juxtaposition with the other member, then fastening such ends to the adjacent supporting members and continuing the process with the second strip and then fastening the edges of the adjacent strips together.

60. 9. The process of erecting a structure, which consists in the following steps, erecting a plurality of supporting members, preparing a relatively narrow elongated metallic strip whose length is greater than the distance between the said supporting members, engaging the strip at its two ends, moving the body as a unit into position in the structure without other support than that engaged at its two ends, and attaching the strip permanently to the supporting member.

65. 10. The process of erecting a structure which consists in the following steps, erecting a plurality of supporting members, preparing a relatively narrow elongated metallic strip whose length is greater than the distance between the said supporting members, engaging the strip at its two ends, moving the body as a unit into position in the structure without other support than that

engaged at its two ends, and attaching the strip permanently to the supporting member, and thereafter similarly moving similar successive strips into position between the supporting members, attaching them thereto and attaching adjoining edges of adjoining strips together.

11. The process of erecting a structure which consists in the following steps, erecting a plurality of supporting members, preparing a relatively narrow elongated metallic strip whose length is greater than the distance between the said supporting members, engaging the strip at its two ends, moving the body as a unit into position in the structure without other support than that engaged at its two ends, and attaching the strip permanently to the supporting member, and thereafter similarly moving similar successive strips into position between the supporting members, attaching them thereto and attaching adjoining edges of adjoining strips together, each strip overlapping one edge of an adjacent strip, whereby it is partially supported thereby.

12. The process of erecting a structure which consists in erecting a plurality of fixed supporting members, preparing a relatively narrow, elongated metallic strip, moving the strip bodily into position in the structure and successively adding to the length of the strip additional strip members as the strip is moved into position in the structure, and permanently attaching the strip to such supporting members.

13. The process of erecting a structure which consists in erecting a plurality of fixed supporting members, preparing a relatively narrow, elongated metallic strip, moving the strip bodily into position in the structure and successively adding to the length of the strip additional strip members as the strip is moved into position in the structure, and permanently attaching the strip to such supporting members, and continuing the process to build up and move into position a second strip, and fastening the adjacent edges of the strips together.

HENRY G. ONSTAD.
